CLAIM

The ornamental design for a pair of shorts, as shown
and described.

DESCRIPTION

FIG. 1 is a front elevation view of a pair of shorts showing my new design;

FIG. 2 is a top plan view thereof;

FIG. 3 is a rear elevation view thereof;

FIG. 4 is a bottom plan view thereof; and,

FIG. 5 is a right side elevational view thereof, the left
side being a mirror image.

The broken lines shown throughout the views are un-
derstood to represent conventional stitching.

*FIG. 1**FIG. 2**FIG. 3**FIG. 4**FIG. 5*
